UNITED STATES PATENT OFFICE

HARLEY J. MEGLEY, OF CHICAGO, ILLINOIS

TYPOGRAPHICAL MOLD

Application filed May 14, 1928. Serial No. 277,755.

This invention relates to typographical molds and more particularly to typographical molds for making type lines or lines of type for multigraph machines, rotary printing machines and the like.

In my prior Patents 1,461,927 of July 17, 1923 and 1,601,221 of September 28, 1926, I have provided molds for casting lines of type with retention means for cooperation with the chases or other retention means in the cylinder or type carrier of the multigraph or other printing machine and with a supplemental gate integrally connected with the printing line through a weak or relatively fragile connecting portion which, after casting the desired line, is adapted to be ruptured or broken off to separate the printing line from the gate. As previously brought out the casting of the line ready for insertion into the grooved or chased holder of the printing machine without the performance of further operations upon it simplifies and decreases the cost of furnishing the type for a desired run on such a machine, simplifies and decreases the cost of setting up the type and using the machine and improves the results obtained.

With the provision of this invention and the inventions of my prior patents above referred to, I have found that the utility of previously existing casting machines may be greatly increased and that multigraph machines have been set up for use in places where they had not been previously used.

It is an object of my present invention to still further simplify and improve the mechanical construction, assembly and relation between the parts of the mold and to still further improve the casting operation and the results obtained.

Another object is to still further increase or improve the adaptability of the mold to different existing casting machines and mold wheels and to further increase or improve the interchangeability with various existing or standard fixed jaw molds for use of either separately or in any desired combination on the same machine.

Another object is to still further prevent "squirting" of type metal between parts

where it might in time interfere with proper closing or functioning of the mold.

Another object is the provision of a simplified and less expensive mold requiring less skill to operate or use and less skill to set up, take care of and remove.

Another object is to make the device even more "fool proof".

Another object is to improve the means for spreading or separating the separable casting jaws and particularly to avoid any possible improper separation that might result from depending upon the coordination and relationship between separating members operating at different points upon the mold.

When the jaw members have been spread or separated by more than one spreading or separating member, the proper separation of the jaws has depended upon the maintenance of a proper relationship between the spreading members. The spreading or separating means of the present invention avoids any objectionable results or improper separation of the jaws because of imperfect alignment of the machine, as well as any improper separation from improper cooperation of a plurality of spreading or separating members with the mold, as well as from warping or distortion of the mold wheel or vise frame or from improper alignment or coordination between the spreader or separating means on the mold and the spreader or separator actuating means on the vise frame.

Another object is the provision of improved means for positively closing the casting jaws and for holding said jaws closed and against movement during the casting operation.

Another object is the provision of an improved mounting and guide means for the jaws and the provision of an improved opening and closing movement therefor.

Another object is the provision of improved means for adjusting the position of the matrix positioning means.

Another object is the provision of means for holding the type line against sticking to the separable casting faces and against distorting or bending, particularly from the fragile connecting portion or neck of the slug in opening the mold.

Another object is the provision of an improved adjustable mounting for the jaw or mold closing means.

Further objects and advantages of the present invention will appear from the following detailed description and the claims, taken with an inspection of the accompanying drawings, in which:

Fig. 1 is a front elevational view of the mold wheel of a type casting machine showing a mold embodying the present invention in connection therewith;

Fig. 2 is a top plan view of the mold;

Fig. 3 is a front elevational view of the mold;

Fig. 4 is a longitudinal horizontal section taken on the line 4—4 of Fig. 3;

Fig. 5 is a plan view of the inner casting face and associated parts of the outer part 20 or cap member of the mold with the outer casting jaw in place thereon;

Fig. 6 is a plan view of the outer casting face of the inner mold part or base member with the inner casting jaw in place;

Fig. 7 is a fragmentary detail section taken on the line 7—7 of Fig. 3;

Fig. 8 is a fragmentary detail section taken on the line 8—8 of Fig. 3;

Fig. 9 is a section taken on the line 9—9 30 of Fig. 3;

Fig. 10 is a rear elevational view showing the back or inner face of the outer casting jaw;

Fig. 11 is a sectional view taken on the line 35 11—11 of Fig. 3 with the separable or spreadable casting jaws in closed position;

Fig. 12 is a view similar to Fig. 11 showing the casting jaws in open position;

Fig. 13 is a diagrammatic side elevational 40 view of the mold wheel, associated vise frame and ejector;

Fig. 14 is a perspective view of one of the jaw opening members at one end of the mold;

Fig. 15 is a perspective view of the other 45 jaw opening member for actuating the member shown in Fig. 14;

Fig. 16 is a perspective view of one of the jaw closing members at the opposite end of the mold;

Fig. 17 is a perspective view of the other 50 jaw closing member for actuating the member shown in Fig. 16;

Fig. 18 is a fragmentary perspective view 55 showing how the casting surface of the mold member may be extended out flush with the outer surfaces of the guiding ribs on the front of the mold member;

Fig. 19 is a more or less diagrammatic front 60 elevational view showing one manner of lubricating the sliding contact between the separable or spreading jaws and the associated mold members;

Fig. 20 is a detail section taken on the 65 line 20—20 of Fig. 18;

Fig. 21 is a detail section taken on the line 21—21 of Fig. 19;

Fig. 22 is a diagrammatic front elevational view showing another embodiment of the invention;

Fig. 23 is a fragmentary perspective view showing the slug or line of type as it is cast;

Fig. 24 is a fragmentary perspective view of the type line with the gate removed;

Fig. 25 is a fragmentary and more or less 75 diagrammatic face view of the vise frame showing the mounting of the jaw or mold closing pin on the left hand vise jaw;

Fig. 26 is an enlarged fragmentary detail section taken on the line 26—26 of Fig. 25; 80 and

Fig. 27 is a fragmentary front elevational view showing liner means along the line of that shown at the left hand end in Fig. 1 at both ends of the casting recess and means 85 on said liner means for holding the slug against sticking to the casting jaws and against distorting or bending.

Referring first to the embodiments illustrated in Figs. 1 to 17, 1 designates any suitable existing or other mold wheel. The mold wheel 1 is shown as provided with openings 2 over which the molds are mounted. The wheel or mold carrier 1 may be adapted for use with any existing or other casting machine and it is adapted to be rotated and moved axially to position the molds successively for the reception of a charge of type metal and for ejection of the slug in the usual or any suitable manner which may, of course, be varied within the scope of the present invention.

For the purpose of the present disclosure, I have illustrated one mold 5 embodying the present invention and one mold 3 which may be of existing fixed jaw form. The molds 3 and 5 are attached to the front face of the wheel or disc 1 and are preferably interchangeable. It will, of course, be understood that more than one of either of said molds may be employed and that they may be attached in any desired relation or combination about the face of the mold wheel or carrier and that the casting machine may be operated with molds of one form on the carrier at one time and with molds of the other form on the carrier at another time, as desired, also that the machine may be operated with both types of molds in combination and at the same time.

In the particular embodiment illustrated and for the purpose of explaining the invention in connection therewith, it will be assumed that the type metal is squirted or run into the molds at the point in the cycle of movement in which the mold 5 is positioned in Fig. 1 and that ejection is effected at the point in which the mold 3 is shown. While this arrangement may also be varied, it will be apparent, as this description proceeds that 125

the means of the present invention is adapted to be embodied and the invention practiced without change or at least, with very little change in the casting machines now in general use. With the present invention four of the molds 5 may be employed on the wheel 1 at the same time without interference with each other.

The mold 5 comprises a base member or inner mold part 6 and a cap member or outer mold part 7. The cap 7 is mounted upon the base 6 with the casting surfaces in opposition. The opposed casting faces of these mold parts are aligned and held in alignment at one side by a dowel pin 8 and at the other side by a screw 9 which binds the base 6 and cap 7 together. The base 6 and cap 7 are provided in the present instance with extensions 10 projecting longitudinally beyond the ends 20 of the mold proper and the under surfaces of these extensions are properly finished to seat upon lugs or blocks 11 carried by and projecting from the face of the wheel 1, the mounting surfaces of the lugs 11 being in alignment and so positioned that when the extensions 10 rest thereupon, the mold will be properly positioned on the wheels 1.

Swiveled screws or bolts 12 pivoted in the lugs 11 are adapted to be swung into slots 13 in the opposite ends of the extensions 10 and the cooperating nuts tightened to clamp the mold securely in place. The mold 3 is similarly clamped in place, as shown. The particular means for clamping or attaching the mold to the mold wheel may be varied as desired, the means shown being illustrative of an ordinary or existing clamping means for clamping either the mold 3 or the mold of the present invention in place upon the wheel.

The inner or under surface of the cap member 7 of the mold 5 is recessed at 14 to form the space 15 in which the gate 114 of the slug line 110 (Fig. 23) is cast. The opposite ends of this relatively fixed casting space 15 are closed or defined by downwardly extending portions 18 formed integral with the cap 7, and constituting in effect the spacers or liners of the mold gate forming means. Where a slug or line of different length or thickness is desired the cap 7 may be replaced with another cap with the projections 18 and recess 14 proportioned to give the desired thickness or length or, of course, the liners may be made in separate interchangeable pieces as well understood in the art.

The outer face of the base 6 is recessed or relieved at 19 to receive a detachable front or outer face plate 20 which extends over the surface 19 and is secured thereto as by means of screws 21.

The two screws 21 to which the lead lines extend are sufficient and the others may be employed or omitted as desired. The upper or outer portion of the surface 19 is further offset or relieved at 22 and the inner casting

jaw 23 is slidably mounted upon the surface 22 with its integral depending flange 25 extending down between the surface 22 and the outer face plate 20. The ledges 26 along the upper edge of the outer or front of the plate 20 constitutes a matrix keeper for proper positioning the line of matrices before the mold, for the casting operation as well understood and the openings in the plate 20 through which the shanks of the screws 21 extend are sufficiently large to provide play therebetween which permits adjustment of the plate 20 and the matrix position ledges 26 carried thereby over the surface 22. Adjustment of the plate 20 to adjust the positioning of the matrices is accomplished by screws 30 which thread through the forwardly extending flange 31 along the lower edge of the base 6 and engage the inner or lower edge of the plate 20. A pair of washers or spacers 33 of equal thickness with one disposed between the bottom or inner edge of the flange 31 and the head of each screw 30 permits them to be drawn up tight to hold the plate 20 and matrix positioning ledge 26 firmly and positively in proper adjusted position. For the purpose of changing the position of the matrix positioning ledge 26 a pair of thicker or thinner washers 34 or spacers (Fig. 3) may be substituted for the washers or spacers 33.

The outer face of the cap 7 is offset or relieved to provide a surface 35 upon which the outer casting jaw 36 is slidably mounted with its lower or inner portion offset at 37 out over the ledge 38 for movement upon the surface 35 and over the outer surface of said ledge 38 in the plane of movement of the cooperating inner jaw 23. The upwardly extending flange 39 of the jaw 36 is provided with a longitudinally extending and rearwardly relieved or offset tongue 40 at each end of the flange 39, these tongues 40 being slidably retained in the adjacent grooved edges 42 of keeper pieces 43, one of which is secured to the front relieved surface 35 of the cap 7 at each of the opposite ends of the outer jaw 36 as by means of a screw 44. Each keeper 43 may be properly positioned or aligned and maintained in proper position and alignment on the cap 7 by means of a pair of dowel pins 45, 45 engaging in suitable openings in the cap 7. The outer jaw 36 is opened and closed by diagonal or oblique outward and inward movement upon the surface 35. The force or effort for opening and closing the outer and inner casting jaws is applied longitudinally and generally parallel with the casting space 15 and for the purpose of directing the outer jaw 36 obliquely under this longitudinal force or effort, the surface 35 is provided with a pair of oblique or diagonal ribs 48 which engage in correspondingly diagonal grooves 49 in the back or rear surface of the jaw 36.

The inner jaw 23 is similarly directed and guided obliquely or diagonally in its open-

ing and closing movement by the engagement of diagonal or oblique ribs 50 on the surface 22 with corresponding diagonal or oblique grooves 51 in the back or rear face of the inner jaw 23. In the particular embodiment disclosed, the inner and outer jaws are directed obliquely both toward one end of the mold in opening and both toward the opposite end of the mold in closing. Obviously, these two jaws may be directed toward opposite ends of the mold in opening and in closing and other variations may be made.

For the purpose of moving the jaws 23 and 36 diagonally outwardly to open the same, I provide at one end of the casting jaws a spreading or jaw separating member 60 which has movement longitudinally of the mold or parallel with the casting space 15 and a transversely movable wedge-like member 62 for actuating the member 60. The separating or spreading member 60 is provided along its upper edge with a rearwardly directed marginal flange 63 which engages over and is guided upon the ledge 38 on the cap 7 and the lower or inner edge of the member 60 has an inwardly directed or depending flange 64 which is slidably held between the outer relieved surface 22 of the base member 6 and the adjacent end of the face plate 20. The rearwardly flanged upper margin 63 is also preferably flanged or extended upwardly slightly at 65 and this upwardly or outwardly extending margin 65 is slidably retained in the grooved margin or edge 66 of the adjacent keeper 43. The keeper 43 at one end of the mold thereby serves as a keeper for one end of the outer casting jaw and as a keeper for the upper edge of the spreading or separating member 60.

The cap 7 is recessed at 68 to receive the spreading member 60 preferably substantially flush with the outer edges of the casting jaws 23 and 36. The jaw end of the member 60 is notched or grooved transversely at 69 and an extension or liner lug 70 preferably integral with the cap 7 fits in the groove 69 and guides the member 60 longitudinally or substantially parallel with the casting space 15. The inner lateral surface of the lug 70 preferably forms a continuation of the corresponding surface of the adjacent projection 18. At its opposite end the spreading member 60 is notched at 71 to receive the wedge-like member 62 for actuating the member 60. The member 62 has a stem 72 which fits slidably in a groove 73 in the adjacent surface of the cap 7 shown in Fig. 4. The outer headed end 74 of the member 62 is provided at 75 with a tapered or wedge-like edge which cooperates with a correspondingly tapered or wedge-like edge 76 on the member 60 at the inner end of the notch 71. When the actuating member 72 is pushed or moved rearwardly as by means of a force applied to the outer surface of the headed end there-

of as indicated by the arrow in Fig. 4, the inclined edge 75 will by its cooperation with the edge 76 force or move the member 60 to the right as viewed in Figs. 3 and 4 and this movement will be transmitted to the spreadable casting jaws 23 and 36 by the engagement of the opposite end of the member 60 with said jaws on opposite sides of the lug 70. Under the force or effort thus imparted longitudinally to the jaws, these jaws will be directed and guided obliquely outwardly away from each other to open the mold for the ejection of the slug or cast line therefrom.

The taper or inclination of the cooperating surfaces 75 and 76 is preferably relatively great so that when the casting jaws are moved obliquely toward each other in closing the mold, as will be described presently, the longitudinal movement imparted to the opening member 60 thereby will move or return the wedge member 62 outwardly to its normal jaw closed position as indicated in Fig. 4.

For the purpose of closing the casting jaws 23 and 36, the opposite end of the mold is provided with a closing member 78 which moves longitudinally or parallel with the casting space 15 similar to the member 60. The closing member 78 is guided and retained along its outer edge by engagement at 79 in the grooved margin of the adjacent keeper 43 and the inner edge of the member 78 is provided with a flange 80 which is retained by the adjacent end of the face plate 20. The closing member 78 is notched or recessed at 81 to receive a wedge-like actuating member 82 similar to the member 62 at the opposite end of the mold. The actuating member 82 is provided with a stem 83 which fits for backward sliding movement in a groove 84 in the adjacent surface of the cap 7. The outer end of the member 82 is headed at 85 and this headed end has a tapered or inclined edge 87 for engagement with a correspondingly tapered or inclined edge 86 on the closing member 78 at the inner end of the notch 81. Similar to the opening wedge 62 the closing wedge 82 is movable transversely and substantially normal to the closing member 78.

When the wedge member 82 is pushed or moved rearward to position in Fig. 4, as by the application of a force indicated by the arrow in Fig. 4, the tapered surface 86 cooperates with the tapered surface 87 and moves the closing member 78 longitudinally or parallel with the casting space 15 to the left as viewed in Figs. 3 and 4. This movement of the closing member 78 is transmitted to the jaws 23 and 36 by its engagement therewith and these jaws 23 and 36 are under the direction and guidance of the oblique ribs 48 and 50 moved obliquely inwardly to closed position.

The opening and closing members 60 and 130

78 may be actuated in any suitable manner. In the present instance, actuation of the jaw opening wedge 62 as indicated by the arrow in Fig. 4 is accomplished by the head of a screw 85 which is secured in a banking block 86 carried by the vise frame 87 as shown in Fig. 13. The head of the screw 85 engages the head of the wedge 62 when the mold wheel is positioned with the mold in ejecting position and moved toward the frame 87.

10 This engagement of the screw 85 with the opening wedge 62 moves or pushes the wedge 62 rearwardly to spread or separate the casting jaws 23 and 36 as already explained.

15 The jaw closing member 78 may also be actuated in any suitable manner. In the present instance, actuation is accomplished by the end of a threaded pin 88 secured in the vise jaw 89 carried by the vise frame 87 and positioned adjacent the member 82 in casting position. When the mold wheel is in casting position and moved toward the frame 87, the head of the member 82 is engaged by the pin 88 as indicated by the arrow in Fig. 4 and moved or pushed rearwardly to close the casting jaws.

20 As in my previous inventions other abutment means than the screws 85 and 88 may be employed and where screws or removable means are used, they may be removed as desirable or necessary when the machine is to be run with the usual or ordinary molds alone or by providing slight recesses in the ordinary molds to receive the heads of the screws, 25 removal is not necessary.

25 From the foregoing, it will now be apparent that the mold is opened by the engagement of a single screw or abutment 85 with the opening wedge 62. The manner of mounting, directing and guiding the jaws 23 and 36 by the ribs 48 and 50 and cooperating grooves 49 and 51 assures uniform and proper opening or separation of the jaws throughout their entire length and without the necessity of additional opening means 30 at the opposite end of the mold. This simplifies and improves the mechanical construction and avoids any possible improper separation that might result from depending upon the coordination and relationship between separating members at the opposite ends of the mold and upon the maintenance of a proper relation of these members with respect to each other. Where the relative positions and movement of two separating members, one at each of the opposite ends of the mold are relied on to open the mold, any misalignment may result in insufficient opening of the mold at one end or other improper opening and with the present provision for opening by engagement at one end only, this is avoided.

35 When the mold wheel is turned to position the mold in casting position and moved toward the vise frame 87, as well understood

in the art, the other screw or abutment 85 by its engagement with the closing wedge 82 forces or moves the casting jaws positively together and into closed position and holds said jaws firmly and positively closed during the casting operation. At this time, the diagonal ribs 48 and 50 assure proper closing of the jaws over their entire length with the closing engagement at one end only. In the casting operation, the type metal is squirted into the casting space 15 and between the separable jaws and with the engagement of the screw 88 with the closing wedge 82, the jaws are held firmly and positively closed and against separation under the pressure of the type metal. At the same time, it will be noted that the jaw closing movement of the member 78 will, through the jaws 23 and 36 move the jaw opening member 60 into position so that when the opening wedge 62 is again pressed in, the jaws will be opened thereby and in the opening movement of the member 60, the closing member 78 is moved through the jaws 23 and 36 into position so that when the closing wedge 82 is again pressed in the jaws will be closed thereby.

30 The inner end 90 (Fig. 3) of the jaw closing member 78 is in constant butt engagement with the adjacent ends of the jaws 23 and 36 and the inner end 91 formed by the inner ends of the liner 70 and opening member 60 is in constant butt engagement with the opposite ends of the jaws. This butt engagement at the opposite ends of the spreadable jaws 23 and 36 performs the additional important function of positively preventing any squirting of the type metal out from the ends of the casting space along the spreadable jaws.

35 Heretofore, when this squirting occurred, it was necessary to take the entire mold apart and clean it. The present invention prevents this squirting and it prevents the type metal from getting in between moving parts where it would impair movement and prevent proper operation. It will also be apparent that in the opening and closing movements of the mold jaws, the ends of these jaws will have a wiping movement across the end surfaces 90 and 91 which is desirable. The end surfaces 90 and 91 and the adjacent and cooperating ends of the jaws 23 and 36 are shown with a slight reverse or V taper at each end. This increases the wiping engagement above referred to, but it is to be understood that these cooperating end surfaces 90 and 91 may be formed square or substantially normal to the plane of the casting space 15.

40 For the purpose of closing or at least urging the jaws 23 and 36 to closed position upon removal of the force for opening and holding the jaws open, a suitable and preferably relatively stiff spring 93 is provided, as shown in Figure 3. The base is relieved slightly at 94 beyond the end of the inner jaw

23, and the spring 93 which is arranged in this recess 94 is looped about a pin or post 95. One arm of the spring 93 is turned down and engaged with the shoulder 96 and the other end is turned up and engaged at 97 with the closing member 78 and tends to move said member 78 to the left as viewed in Fig. 3 when the opening member is released. Movement of the member 78 in this manner under the action of the spring 93 will close the casting jaws when the opening member is released.

In case of incomplete closure under the action of the spring, the closing screw or abutment 85 will upon engagement with the closing wedge 82 positively close the jaws of the mold and hold same positively closed during the squirting and casting operations.

The opposing casting faces of the separable or spreadable jaw members 23 and 36 are provided with longitudinally extending tongues or ridges 100 (Figs. 11 and 12) for forming the desired grooves in the opposite sides of the line portion of the slug in the casting operation. Of course, these opposing casting faces may be formed to provide any other suitable or desired retention means along the type line for mounting and holding the same in the particular multigraph machine, rotary press or other machine in which the type line is to be used. Spaced inwardly slightly from the tongues or ridges 100, the casting faces of the jaws 23 and 36 are provided with shoulders which extend into close proximity to form the bottom surface of the type line. The casting faces of the jaws 23 and 36 are provided with shoulders which extend into close proximity to form the bottom surface of the type line. The casting faces of the jaws are inclined or tapered from the reduced mold opening or neck thus formed to the rear relatively fixed casting surfaces of the base member 6 and cap member 7, as shown at 102 in Figs. 11 and 12. One end of the casting space between the jaws 23 and 36 is defined directly by the surface 90 of the closing member 78 and the opposite end of this casting space is defined by the surface 91 of the lug 76.

In operation the mold wheel 1 is rotated to position the mold 5 for the casting operation, in this instance the position shown in Fig. 1. In this position the mold wheel is moved toward the vise frame and the single jaw closing abutment 88 thereon engages the closing wedge 86 and positively closes the jaws and holds same positively closed and against separation in the casting operation. The type metal is then squirted or run into the mold between the base and inner jaw member on one side and the cap and outer jaw member on the other side. After the casting of the slug, the mold wheel is revolved or turned to position the mold 5 in the position in which the mold 3 is shown

in Fig. 1. The axial movement at this point engages the head of the screw or abutment 85 with the opening wedge moving said wedge rearwardly and spreading the jaw members of the mold apart to permit ejection of the type line. When the jaws are opened, the ejector blade 105 (Fig. 13) is projected into engagement with the inner edge of the gate of the slug and forces the slug out from the mold between spaced knife members 106 which trim the slug and remove any burs although this may, of course, be varied widely within the scope of the present invention.

The finished slug is shown in Figs. 23 and 24. It comprises the type or line of type 110, the height h which is adapted for arrangement in the printing machine. This type line 110 is joined through a reduced weakened or relatively fragile connecting portion 112' with a gate 114 which makes up the width or height which is formed in the casting machine.

The outer or upper face of the line 110 carries the printing characters or letters 115 formed in the embodiment shown by running the molten type metal into the desired line of matrices assembled in the vise jaws in the usual manner. The grooves or nicks 116 cast in the opposite sides of the line provide for mounting and holding the same in the multigraph machine, rotary press or the like. The casting of these type lines may be varied, as already pointed out, according to the particular ward or mounting arrangement provided in the machine with which the type is to be used. The height h of the type line from the outer face to the bottom or base 112 may likewise be varied, as may the particular characters 115 formed on the printing face thereof. The line 110 so cast is separated from its gate 114 by rupturing or breaking the relatively weak or fragile connecting portion 112' upon or after ejection from the casting mechanism, giving the desired line ready for insertion into the printing machine with which it is to be used without further operations upon it.

In Figure 18, I have shown how the outer casting surface of the base member 6' may be extended out flush with the outer surfaces of the ribs 50' as indicated at 125. The inner casting surface of the cap member may be similarly extended out flush with the outer surfaces of the ribs 48. Where these casting surfaces are extended out flush with the outer surfaces of the ribs, the extension will be in the form of a marginal rib or ledge and the associated movable casting jaw will preferably be grooved to fit over this ledge 125 in closed position.

In Figure 19, I have shown one manner of lubricating the sliding contact between the spreadable jaws and the associated mold members. In this case the cap 130 is pro-

vided with a pair of lubricant or oil ducts 132, the outer ends of which may be provided with spring pressed ball or other suitable closures 133. The inner ends of the ducts 132 open at 134 through the ribs 135 and to the outer surfaces thereof for delivering the lubricant supplied through the inlets 133 to the slidingly engaging faces between the cap 130 and the outer movable jaw member. The base 135 is similarly provided with a pair of ducts 137 provided at their outer inlet ends with suitable closures 138 and opening at 139 to the slidingly contacting surfaces. In Figure 21, I have shown the details of one form of closure for the outer ends of the ducts 132 and 137. This closure may be opened by insertion of the neck or spout of the oil can and is closed by the spring shown. The closure may, of course, be varied as desired.

In Figure 22 I have shown in place of the spring 93 previously referred to a pair of springs 140 for urging or yieldingly moving the outer jaw to closed position and a pair of springs 142 for yieldingly moving the inner jaw to closed position. In this case the grooves are shown as being disposed in the base and cap of the mold with the ribs 48' and 50' (shown in section) integral with the separable jaws and engaging in the grooves. The springs 140 and 142 are shown as acting substantially parallel with the ribs 48' and 50' and the outer ends of the base and cap openings for said springs are shown as closed by plugs 160 which may be adjustable for the purpose of adjusting the tension of said springs.

The particular mounting and arrangement of these springs may be varied and any suitable arrangement may be provided for adjusting the tension thereof as for example, along the line of the disclosure of my prior Patent 1,601,221 previously referred to.

The jaw or mold closing pin 88 of Figures 25 and 26 is preferably adjustably threaded into the vise jaw 89 at 162 and has a lock washer 163 threaded thereon and adapted for locking or securing the pin 88 in different adjusted positions.

The opening and closing members 62 and 82 are restrained from complete accidental displacement from the mold by pins or fingers 165, 166 (Figures 8 and 9) which engage in grooves 167 and 168 respectively in the upper or outer surface of the mold base 20.

The liner 70 at one end of the casting space in Figure 3 may be and is preferably duplicated at the opposite end of the casting space as shown at 170 in Figure 27 and these liners 70 and 170 are preferably provided with ribs 180, 180 or other suitable means for engaging and interlocking with the opposite ends of the cast slug to hold the slug from sticking to the casting jaws and against distorting and bending, particularly against distorting and

bending from the neck of the slug in opening the mold.

I claim:—

1. In combination, a standard type line casting machine, a mold adapted for use thereon and adapted for casting a type slug, said mold having jaw means movable into open and closed positions and singly actuated means for moving said jaw means from one of said positions to the other independently of the type slug. 70

2. In combination, a mold wheel of the usual formation, a mold adapted for use thereon, said mold having jaw means movable into open and closed positions generally radial of the mold wheel, and singly actuated means for moving said jaw means from one of said positions to the other. 80

3. In combination, a vise frame, a mold wheel movable relative thereto, a mold adapted for use on said mold wheel and having jaw members movable into open and closed positions and singly actuated means for moving said jaw members from one of said positions to the other by the relative movement between said mold wheel and said vise frame. 85

4. In combination, a mold wheel, a vise frame, a mold device attached to the mold wheel, said mold device including a spreadable jaw portion and singly actuated means carried by the vise frame for spreading said jaw portion to release the slug. 90

5. In combination, a mold wheel, a mold of the usual formation adapted for attachment to said mold wheel, a mold device adapted for casting a type slug and comprising a body portion and a spreadable jaw portion adapted for attachment to the mold wheel and for selective use with said first mold, and singly actuated means for spreading said spreadable jaw portion independently of the type slug. 100

6. In combination, a mold wheel having the usual receiving openings, a mold of the usual formation adapted for mounting in one of said openings and for attachment to said mold wheel, said mold being adapted for casting a type slug, a mold device comprising a body portion having opposed stationary casting faces and a spreadable jaw portion having opposed spreadable casting faces adapted for mounting in another of the usual mold openings of said wheel and for attachment to said wheel with said first mold in place, and singly actuated means for spreading said spreadable casting faces independently of the type slug. 110

7. In combination, a mold wheel, a mold device attached thereto and adapted for casting a type slug, said mold device including a stationary body portion constituting a mold for a portion of the opposite faces of the slug, a spreadable jaw portion constituting a mold for another portion of said faces, and singly actuated means for spreading said jaw por- 125

130

tion independently of movement of the slug from the mold to release the slug.

8. In combination, a mold wheel, a mold device adapted for attachment thereto, said mold device including a body portion constituting a mold for a portion of the opposite faces of the slug, an obliquely spreadable jaw portion constituting a mold for another portion of said faces, and singly actuated means independent of movement of the slug from the mold for spreading said jaw portion to release the slug.

9. In combination, a mold wheel, a mold device adapted for casting a type slug comprising a stationary body portion constituting a mold for a portion of the opposite faces of the slug, a spreadable jaw portion constituting a mold for another portion of said faces and adapted for attachment as a unit with said stationary body portion to the usual or standard mold wheel and singly actuated means for spreading the spreadable jaw portion independently of the type slug.

10. In combination, a mold wheel, a mold of the usual formation adapted for attachment to said mold wheel adapted for casting a type slug, a mold device for casting a slug with retention means for securing the same in a type holder or carrier, said mold device being adapted for selective use with said first mold and having a spreadable jaw portion for permitting ejection of the slug and singly actuated means for spreading said spreadable jaw portion independently of the type slug.

11. A mold of the class described adapted for casting a type slug comprising, a body portion and a jaw portion for casting a slug with retention means for securing the same in a type holder or carrier, said jaw portion being spreadable to permit ejection of the slug and being adapted to be assembled and mounted as a unit with said body portion upon the usual or standard mold wheel, and singly actuated means for spreading said jaw portion independently of the slug.

12. In a mold of the class described, a pair of jaw members defining the casting space and adapted to be opened and closed, means at one end of the casting space for opening said jaw members and means at the opposite end of said casting space for closing said jaw members.

13. In a mold of the class described, a pair of jaw members defining the casting space and adapted to be opened and closed, means at one end of the casting space for opening said jaw members, means at the opposite ends of said casting space for closing said jaw members, said opening and closing means each comprising a member movable in a plane parallel with the plane of the casting space and a wedge-headed and transversely movable actuating member.

14. In a mold of the class described, a pair

of jaw members defining the casting space and adapted to be opened and closed, means at one end of the casting space for opening said jaw members, means at the opposite end of said casting space for closing said jaw members, said opening and closing means each comprising a member movable in a plane parallel with the plane of the casting space and a wedge-headed and transversely movable actuating member, a vise frame, and means on the vise frame for actuating said actuating members.

15. In combination, a mold wheel, a mold adapted for use thereon and having jaw means adapted to be opened and closed, a vise frame, and means on the vise frame for moving said jaw means to closed position.

16. In combination, a movable mold wheel, a mold adapted for use thereon and having jaw means adapted to be opened and closed and means actuated by the movement of the mold wheel for moving said jaw means to closed position.

17. In combination, a mold wheel of usual or standard form, a mold adapted for use thereon and having jaw means adapted to be opened and closed and rigidly acting means for positively moving said jaw means to closed position.

18. In combination, a mold having jaw means adapted to be opened and closed, means for opening said jaw means, spring means for urging said jaw means to closed position upon release of said opening means and separate rigidly acting means for positively moving said jaw means to closed position in the casting position of said mold.

19. In a mold of the class described, a jaw member defining one side of the casting space and movable obliquely relative thereto.

20. In combination, a mold member, a jaw member defining one side of the casting space and cooperating guide and directing means between said jaw and mold members for directing said jaw member obliquely toward and from said casting space.

21. In a mold of the class described, a pair of jaw members defining the casting space and adapted to be opened and closed, means at one end of the casting space for opening said jaw members, means at the opposite end of said casting space for closing said jaw members, said opening and closing means each comprising a member movable in a plane parallel with the plane of the casting space and a wedge-headed and transversely movable actuating member, a vise frame, means on the vise frame for actuating said actuating members, and oblique guide means for directing said jaw member obliquely from said opening uniformly over the entire length of said space.

22. In a mold of the class described, a jaw member defining one side of the casting space, an opening member movable in a plane

parallel with the plane of said space and adapted for opening said jaw member, and a transversely movable member for actuating said opening member.

23. In a mold of the class described, a jaw member defining one side of the casting space, an opening member movable in a plane parallel with the plane of said space and adapted for opening said jaw member, and a transversely movable member for actuating said opening member, said opening and actuating members having cooperating inclined surfaces.

24. In combination, a mold wheel of usual or standard form, a mold adapted for use thereon and comprising a jaw member defining one side of the casting space and a closing member movable in a plane parallel with the plane of said space and adapted for closing said jaw member.

25. In a mold of the class described, a jaw member defining one side of the casting space, a closing member movable in a plane parallel with the plane of said space and adapted for closing said jaw member, and oblique guide means for directing said jaw member obliquely toward said space uniformly over the entire length of said space.

26. In a mold of the class described, a jaw member defining one side of the casting space, a closing member movable in a plane parallel with the plane of said space and adapted for closing said jaw member, and a transversely movable member for actuating said closing member.

27. In combination, a pair of spreadable jaw members defining a casting space and a jaw actuating member directly closing the end of said space and having butt contact with the ends of said jaw members.

28. In combination, a pair of spreadable jaw members defining a casting space, opening means for said jaw members at one end of said casting space, closing means for said jaw members at the opposite end of said casting space, said opening and closing means contacting with the ends of the jaw members and directly closing the ends of the casting space and having butt contact with the ends of the jaw members.

29. In combination, a mold having jaw means forming a casting space adapted to be opened to release the slug, liner means closing the end of said space and means on said liner means for engaging the slug and holding same against sticking and against distortion and bending by the opening of the jaw means.

In witness whereof, I hereunto subscribe my name this 12th day of May, 1928.

HARLEY J. MEGLEY.
